Primary Examiner — Kevin Rudzinski(74) *Attorney, Agent, or Firm* — Lathrop & Gage LLP(57) **CLAIM**

The ornamental design for an LED light fixture, as shown and described.

DESCRIPTION

FIG. 1 is a perspective view of a LED light fixture, showing the new design;

FIG. 2 is a top plan view of the LED light fixture;

FIG. 3 is a bottom plan view of the LED light fixture;

FIG. 4 is a side elevation of the LED light fixture, an opposing side elevation of the LED light fixture being identical; and,

FIG. 5 is an end elevation of the LED light fixture, an opposing end elevation of the LED light fixture being identical.

In all of FIGS. 1 through 5, dashed lines indicate environmental structure that forms no part of the claimed design.

1 Claim, 5 Drawing Sheets See application file for complete search history.
